REMOVABLE TOP CONTAINER ADAPTED FOR MOUNTING ON A ROAD VEHICLE

Charles R. Gretz, Valdosta, Ga., assignor, by mesne assignments, to Terraquatics, Inc., a corporation of Florida

Filed May 19, 1969, Ser. No. 17,227

Term of patent 14 years

Int. Cl. D12—06

U.S. Cl. D71—1

FIG.1

FIG.2

FIG.5

FIG.3

FIG.4

FIG.6

FIG. 1 is a left front perspective view of a removable top container adapted for mounting on a road vehicle showing my new design;

FIG. 2 is a left side elevational view thereof;

FIG. 3 is a front elevational view thereof;

FIG. 4 is a rear elevational view thereof;

FIG. 5 is a partial cross-sectional view thereof taken along line 5—5 of FIG. 2; and

FIG. 6 is a left rear perspective view thereof with the top removed therefrom.

I claim:

The ornamental design for a removable top container adapted for mounting on a road vehicle, substantially as shown.
